CLAIM

The ornamental design for a photoelectric timer, as shown and described.

DESCRIPTION

FIG. 1 is a front view of a photoelectric timer showing the preferred embodiment of my new design;

FIG. 2 is a right side elevational view thereof;

FIG. 3 is a bottom view thereof;

FIG. 4 is a top view thereof;

FIG. 5 is a left side elevational view thereof;

FIG. 6 is a rear elevational view thereof; and,

FIG. 7 is a perspective view thereof.

The cord of the timer in FIGS. 1-2 and 5-6 is shown broken away to indicate indeterminate length.
